UNITED STATES PATENT OFFICE.

FRANK P. JOHNSON, OF DANVILLE, PENNSYLVANIA.

CARPET BEATER.

Application filed July 16, 1926. Serial No. 122,866.

This invention relates to carpet beaters and is designed as an improvement on the structure shown and described in Patent No. 1,068,776, issued to me July 29, 1913 on a carpet beater.

In the practical use of and experimental work with devices of this character, when constructed in accordance with said patent and as embodied in other forms now on the market, it has been found that the tendency of the beating head is to elongate when the blow is delivered on the rug or carpet in a well known manner. This is followed by an immediate contraction of said head after the blow and such constant, violent action in the wires or strands comprising the head of the beater soon results in a crystallization of the same with a consequent breakage that renders the beater unfit for use.

The object of the present invention is to so form and strengthen the structure comprising the beating head as to effectually prevent such longitudinal expansion and contraction, thus greatly prolonging the life of the beater, and at the same time to provide for the necessary resiliency required to dislodge the dirt from the article being cleaned.

Another object is to strengthen the shank or stem of the beater, especially where the same is joined to the operating handle, and yet retain the necessary flexibility at that point, as well as throughout the structure, to allow the device to properly accommodate itself to the inequalities encountered in the surface of the carpet or rug.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claim.

In the drawing, in which similar reference characters designate corresponding parts throughout the several figures:—

Figure 1 is a plan view of the improved carpet beater, a portion of the operating handle being shown.

Figure 2 is a similar detached view showing the formation of one of the strands or lengths of wire used in forming the beater.

Figure 3 is a similar view of the other wire member detached.

Figure 4 is an enlarged, longitudinal section through the socket for the operating handle.

In the construction of the improved carpet beater two separate strands or lengths of suitable wire are used, the same being of equal length and of relatively heavy gage so as to withstand the great strain to which the device is subjected in use. These strands are crossed at points intermediate of their ends, as indicated at 1, and are twisted or wrapped together for a distance to form what may be termed a front stem portion 2 located at the outer or front end of the beater head and at the longitudinal center line thereof.

That portion of the wires extending from the inner or rear end of the stem portion 2 are then extended outwardly at angles of approximately forty-five degrees to form angular front struts 3 and 4 respectively, while the portions of the wires extending from the front end of said stem 2 are bent around to the left and the right respectively, in a substantially semi-circular shape to intersect the outer ends of the said struts 3 and 4 and form front corner loops 5 and 6, said wires being brought inwardly towards the center of the beater, where they are twisted, as at 7 and 8, with the wires constituting the said front struts, to form what may be termed side locks.

The wires of the front loops 5 and 6, where extending from the twisted side locks 7 and 8, are then bent inwardly toward the longitudinal axis of the beater, at an angle of substantially forty-five degrees, to constitute angular rear struts 9 and 10, which in conjunction with the front struts 3 and 4 provide a very strong and rigid structure allowing a central opening substantially as large as the said corner loops.

The remainder of the wire comprising the rear struts 9 and 10, where intersecting each other at the longitudinal center of the beater, are then twisted together for the remainder of their lengths to provide a rear stem portion 11, spaced from the front stem portion and in longitudinal alignment therewith though considerably longer than the same, and having the terminals 12 and 13 of the

wires separated or spread apart at an angle as clearly shown in Figure 4 of the drawing.

The remaining portions of the wires constituting the front struts 3 and 4, where extending from the side locks 7 and 8, are then bent rearwardly and inwardly towards the rear stem 11, to form rear corner loops 14 and 15 similar in shape and size to the front loops and providing a beater head having five substantially equal openings as comprised by the front and rear struts and the corner loops.

The wires constituting the rear corner loops 14 and 15 are then wrapped tightly about the rear portion of the rear stem 11, for several turns, as indicated at 16 and 17, the latter coils interlocking with the coils of the said stem and the remainder of said wires are then formed into circular coils 19 of larger diameter, the coils of one wire alternating with the coils of the other to form a handle socket 20 into which may be screwed a suitable wooden or other handle 21, the coils 20 serving as threads and the ends of the wires 22 tightly hugging the handle so as to avoid injury to the carpet or rug, and at the same time concealing and locking the ends 12 and 13 of stem 11 thereby providing anchorage against elongation.

It will be seen, by reference to Figures 2 and 3 of the drawing, that the lengths of wire comprising the beater, though simultaneously formed during the aforesaid bending and twisting operations, constitute closed members A and B, disposed at opposite angles relative to the longitudinal axis of the beater, and that each includes a front and a rear corner loop diagonally opposite to each other, and joined together by the aforesaid angularly disposed front and rear, parallel struts, the said front loops each having one strand of the front stem included therein and the said rear loops each having one strand of the handle socket included.

The prevention of longitudinal, sliding movement of the handle socket on the rear stem portion is aided, in addition to the interlocking of the twists 16 and 17 with the twists of the rear stem, by the out-turned terminals 12 and 13 which are located at the inner end of the socket and bear against the same.

Any tendency to elongate, while in use, is prevented in the beater by the provision of the side locks 7 and 8 and by crossing the front and rear strut wires and continuing the same to form the rear and front corner loops respectively.

From the foregoing it will be seen that a simple and cheaply constructed device has been provided of strong and durable construction which will retain its shape under constant usage and prevent the usual elongation and other distortion which causes crystallization of the wire comprising the same and the consequent breaking of the same.

What is claimed is:—

A beater composed of a pair of wires twisted together at separate points intermediate their ends and arranged to form a series of struts and loops of relatively short lengths, the ends of the loops being braced by the struts arranged in opposite pairs one pair of free end portions of the wires constituting the rear pair of loops and being twisted together and presenting interlocking coils to provide a handle socket, the other pair of free end portions of the wires constituting the adjacent struts and being brought together and twisted to constitute a flexible rear stem, the ends of the stem wires being bent outwardly to engage within the coils of the socket and concealed therein, and the loop wires adjacent to the interlocking coils of the socket being wrapped tightly about the stem to prevent a relative longitudinal movement of the latter.

In testimony that I claim the foregoing as my own, I have hereto affixed my signature.

FRANK P. JOHNSON.
